UNITED STATES PATENT OFFICE

JAMES D. COLE, OF CLEVELAND HEIGHTS, OHIO, ASSIGNOR TO THE DOMESTIC ELECTRIC COMPANY, OF CLEVELAND, OHIO, A CORPORATION OF OHIO

EXERCISING DEVICE

Application filed May 21, 1929. Serial No. 364,785.

The general object of this invention is to provide an improved and simplified exercising and massaging device or apparatus of the type shown, for example, in my prior application, Serial No. 315,858, filed October 29, 1928.

Exercising and massaging machines for giving what may be generically termed kinetherapeutic treatments have been used, which, with various adjustments, may be employed to exercise and massage the human body or parts thereof, as by the use of a belt embracing such body or parts, and to give treatment which is more strictly exercising treatment. An example of the latter treatment is where the user grasps a pair of rapidly reciprocating elements of the machine with his two hands, and is exercised by offering resistance to the operation of the machine.

An object of the present invention is to provide a machine wherein both types of treatment may be given interchangeably without loss of time in having to effect tedious adjustments. A further object is to provide an exercising and massaging device which will enable both types of treatment above mentioned to be effected at reduced installation cost.

A specific object is to provide an applicator for use with an exercising and/or massaging machine which shall be so arranged that the user may massage while exercising various parts of his body, using the applicator as a belt and, without adjustment of the machine, vigorously exercise his arms and shoulders.

The invention, as illustrated, comprises a flexible exercising and massaging belt of suitable length provided with means for connection to the vibrating elements of an exercising machine, the belt having incorporated therewith a pair of flexible hand hold members adapted to be gripped by the hands of the user. The hand hold members are illustrated as loops preferably formed by strips of web material similar to, but narrower than that of the belt, the ends of such narrow strips being attached, as by stitching, to the flat sides of the belt.

The various advantages of the invention will become apparent from the following description relating to the accompanying drawings showing the preferred form. The essential novel characteristics are summarized in 55 the claim.

Referring briefly to the drawings, Fig. 1 shows a side elevation of a suitable exercising machine and applicator device embodying my invention; Fig. 3 is a plan view of the 60 applicator, and Fig. 2 is a fragmentary side elevation showing more in detail the preferred construction of one of the hand grip elements.

The drawings show in Fig. 1, an exercising machine, the belt vibrating or reciprocating elements of which are crank pins oppositely disposed with reference to the crank axis, so as to alternately pull on the ends of the belt, designated 1. It is to be understood 65 that the machine shown is by way of example, and further, that the applicator apparatus may be modified to operate in connection with any machine, the operation of which is essentially similar.

The exercising machine illustrated comprises an electric motor M provided with an energizing switch S, a casing C for suitable gearing, and a shaft D driven by the gearing. The shaft D carries a pair of discs D', 80 one only being shown, both of which have crank pins P with suitable heads, which pins may be adjusted with reference to the discs so as to vary the effective length of the crank arms to thereby adjust the length of the belt 85 vibrations. A suitable support for the motor and associated mechanism may comprise an underhanging bracket B on the motor frame, adapted to be attached to a suitable support, a door in a building for example. 90

The belt 1 may comprise a suitable length of cloth webbing, and has at its ends reinforced eyelets 2, preferably leather overlays which are provided with keyhole slots 3 adapted to be slipped over the respective 95 heads of the crank pins P. In its ordinary use, the belt is simply placed in contact with whatever part of the body it is desired to massage or exercise and the rapid alternate pulls on the ends of the belt, due to the op- 100

posed relationship of the crank pins, exercises or massages the body with varying force, depending largely on the degree of resistance offered to the pulling impulses by the weight or strength of the user.

A number of machines now on the market are provided with special hand grip members which replace the belt when it is desired to exercise the arms and shoulders. I propose to embody hand grip loops 5 in the belt construction in such manner that these loops may be used when desired without having to remove the belt from the machine and without in any way interfering with the ordinary use of the belt, as above discussed. As shown, the hand grip members 5 comprise simply closed loops of webbing material similar to that of the belt and about half the width thereof, the ends 5a of the strips comprising the loops being simply stitched onto the webbing of the belt, as at 6, the two ends lying in vertical alignment i. e. in a common plane parallel to the wider surface of the belt.

As a matter of course, suitable means may be provided for adjusting the length of the belt portion between the hand grip element 5, so that the two forms of exercise above discussed, may be carried out simultaneously by different sized persons. There are many common types of adjustment for belts, hence, this needs no illustration. In the preferred construction there is no adjustment.

It will be seen from the above description that whenever the user wishes to discontinue the exercise and massage of his body by means of the belt 1, he does not have to remove the belt before taking the arm and shoulder exercise, but simply allows the portion of the belt intermediate the loops 5 to depend idly, while he grasps the two loops, as suggested in Fig. 1.

It will be further seen that the arrangement is extremely simple and cheap to manufacture; that it takes up practically no more space than does the ordinary belt without provision for hand grips; that it does not interfere with packing and shipping by impairing the flexibility of the belt, and that it does away with the necessity for modifying the machine to provide special hand grips thereon.

I claim:

A belt for an exercising machine of the class described, comprising a main flexible strip, means for attaching the ends thereof to the vibrating elements of an exercising machine with the strip extending in a U-course, and a plurality of narrower flexible U-shaped loops permanently attached at their end portions to the outer sides of the main strips in regions between the attaching ends of the main strip and the U-bend thereof, the ends of said narrower strips being secured flatwise side by side in a common plane and

lying substantially entirely within the side boundary of the main strip, said attaching loops extending in the direction toward the U-bend of the main strip, whereby the narrower loops form hand grips.

In testimony whereof, I hereunto affix my signature.

JAMES D. COLE.
